UNITED STATES PATENT OFFICE.

WILLIAM WILKINS AND NELSON C. POE, OF GREENVILLE, SOUTH CAROLINA.

CULTIVATOR.

SPECIFICATION forming part of Letters Patent No. 629,639, dated July 25, 1899.

Application filed September 28, 1897. Serial No. 653,298. (No model.)

To all whom it may concern:

Be it known that we, WILLIAM WILKINS and NELSON C. POE, citizens of the United States, residing at Greenville, in the county 5 of Greenville and State of South Carolina, have invented a new and useful Cultivator, of which the following is a specification.

Our invention relates to an improvement in cultivators of the class usually employed to for cultivating cotton, corn, and other crops; and the objects of our invention are to simplify the construction of the cultivator, reduce the cost of its manufacture, and enable the plow-feet to be attached to the beam in 15 a variety of positions and arrangements with reference to each other, thereby adapting the cultivator to be used under varying conditions and to accomplish different kinds of work.

In the accompanying drawings, Figure 1 is 20 a top plan view of our improved cultivator. Fig. 2 is a side elevation of the same. Fig. 3 is a detail view of the beam.

In the construction of our improved cultivator we employ a beam *a*, which is composed 25 of a single straight bar of steel or iron of suitable length, breadth, and thickness. At the front end of the bar are formed the usual hook *b* and the link *c* for the attachment of the singletree, and the rear end of the beam 30 is upturned at an angle of about thirty degrees for a considerable distance to form the stock *d*, to which are bolted the lower ends of the handles *e* by means of a pair of bolts *f*, which pass through openings made in the 35 upturned stock and in the lower ends of the handles. A rung *g* connects the handles at a suitable point and serves to spread them apart. It will be observed by reference to the drawings that the thickness of the handles 40 is steadily reduced from their outer to their lower ends, so that the lower portions of the handles, which are adapted to bear against the upturned rear end of the beam, are so reduced in thickness that they are capable of 45 being bent to lie against the opposite sides of the upturned rear end of the beam and are held in position by the bolts *f*, which construction of the beam and handles enables the latter to be fashioned and secured to the 50 beam without being cut across or diagonally

with the grain of the wood, the handles being sprung or bent into shape at their lower ends to conform to the upturned rear end of the beam, and hence they are not weakened by cutting or shaping them in the manner now 55 usual in the construction of implements of this class.

Beginning at a point near the center of the beam and extending to near the upturned rear end thereof are a series of six bolt-holes 60 *h*, which are spaced equally distant apart and serve for the attachment and adjustment of the cultivator feet or stocks *i k l*.

The cultivator feet or stocks *i l* are each made of a single piece of bar iron or steel of 65 the same breadth and thickness as that employed in the manufacture of the beam, and said feet or stocks *i l* are adapted to work on opposite sides of the beam, each having the angular wing *m*, the standard *n* at the rear 70 end thereof for the attachment of a suitable cultivator-tooth, and the forwardly-extending arm *o*, adapted to lie snugly against one side of the beam and having a pair of bolt-holes which are adapted to register with a pair of 75 the bolt-holes with which the beam is provided, whereby the cultivator stocks or feet can be readily attached to or removed from the beam or secured at any desired adjustment thereon by means of bolts *p*. The wing 80 *m* of the stock or foot *l*, which is adapted to operate on the left-hand side of the beam, is considerably longer than the wing of the stock or foot *i*, which is adapted to operate on the right hand side of the beam, and when 85 the said stock *i* is secured to the beam by the foremost pair of bolt-holes in the latter and the bolts and the stock or foot *l* is secured to the beam by employing the next pair of bolt-holes, as shown in the drawings, the 90 standard of the stock *l* will be at a distance in rear and to one side of the beam and the standard of the stock *i* will be considerably in advance of said standard of said stock *l* and to the opposite side of the beam, so that 95 the cultivators or teeth attached to said standards will be arranged in a diagonal line with relation to the length of the beam at about forty-five degrees, one in advance of the rear end of the beam and the other at a corre- 100

sponding distance behind the rear end of the beam, which diagonal line x , Fig. 1, is intersected by a line y , Fig. 2, drawn longitudinally through the center of the upturned end of the beam to which the handles are attached, whereby the draft is balanced on opposite sides of the beam and all side strains on the handles are obviated, the angle of the handles and their position on the rear end of the beam being such that they are subjected only to longitudinal stress and all side stress is obviated. This enables us to dispense with braces for the handles without at all impairing their strength or durability, and, moreover, this arrangement of the handles with relation to the line of draft renders it much easier for the plowman to control the implement and materially reduces the necessity for muscular effort. The stock or foot k is also made of a piece of bar iron or steel of similar size to that employed for the beam; but the said stock or foot k is simply formed of the arm, adapted to be bolted to the rear portion of the beam at the rearmost pair of bolt-holes, and the standard r . This standard is shorter than the standards of the stocks i l , so that the cultivator-tooth attached to it will not run so deeply as the cultivator-teeth attached to the standards of the outer feet or stocks, and the draft will be greatest at the outer cultivator-teeth, which arrangement and construction is advantageous for the reason that it causes the implement to run much steadier, reduces side strains, and reduces the labor of the plowman.

It will be noticed that the cultivator-tooth attached to the center stock k operates in the diagonal line x , before referred to, when the stocks are arranged as shown in the drawings, which is the normal and usual arrangement

and the one most frequently employed; but it will be understood, as before stated, that the cultivator-stocks are capable of attachment to the beam and of operation in a variety of arrangements, and one or more of them may be discarded, if preferred or as may be rendered necessary by the work to be accomplished. 45

Having thus described our invention, we claim— 50

1. The cultivator comprising the beam formed of a straight flat bar of metal, having the upturned rear end and the series of equally-spaced bolt-holes h , extending from near the rear end to about the center of the beam; the handles bolted to the upturned end of the beam; the side stocks i , l , each formed of a single flat bar of metal, bent angularly to form the arm o , angular wing m , and downcurved to form the standards n ; the wing of the stock i being materially shorter than the wing of stock l ; and the center stock k , formed of a metal bar adapted to be bolted to the beam at the rearmost pair of bolt-holes, and downturned to form the standard r , said standard being shorter than the standards n , substantially as described. 60

2. In a cultivator, the beam, the central cultivator-stock having the standard, the side cultivator-stocks having the standards of equal length and of greater length than that of the center stock, whereby the side cultivator teeth or plates will run deeper than the tooth or plate of the center cultivator, for the purpose set forth, substantially as described. 70 75
